UNITED STATES PATENT OFFICE.

RALPH MELLOR, OF PHILADELPHIA, PENNSYLVANIA, ASSIGNOR TO KESTNER EVAPORATOR COMPANY, OF PHILADELPHIA, PENNSYLVANIA, A CORPORATION OF PENNSYLVANIA.

EVAPORATOR.

1,424,254.

Specification of Letters Patent. Patented Aug. 1, 1922.

Application filed August 9, 1920. Serial No. 402,374.

To all whom it may concern:

Be it known that I, RALPH MELLOR, a citizen of the United States, residing at Philadelphia, in the county of Philadelphia 5 and State of Pennsylvania, have invented certain new and useful Improvements in Evaporators, of which the following is a specification.

This invention relates to evaporators; and 10 it comprises an evaporator having a plurality of tubular heating elements arranged in vertical series with a substantially continuous evaporating tube passing through the several elements, the elements in each 15 tier having a trapped liquid drain to the element below whereby to by-pass condensed steam out of the path of heating vapors going through the series; and it more particularly comprises an evaporator of such a 20 type wherein the trapped liquid drain is formed by cooperating and complementing unions, each said union having a flanged passage provided with a cup-like element having a portion extending beyond the 25 flange plane and the elements being so shaped that on assemblage of two unions they together form a liquid-sealed trap; all as more fully hereinafter set forth and as claimed.

30 In the well known Kestner type of evaporator, evaporation is performed on what is termed a "climbing film"; liquid goes upward through a steam or vapor heated vertical tube, first as a sort of foam and 35 finally as an annular ascending film with a central current of vapor travelling at a rather high velocity. For reasons of space it is sometimes desirable to use the same type of apparatus and operation in 40 horizontal tubes rather than vertical; the evaporator tube being constituted of a plurality of superimposed horizontal end-connected tube sections. In so doing, the surrounding heating element or jacket is likewise made as a series of superimposed sections connected together. In practice it is 45 desirable that these jacket sections be rather narrow, giving a narrow annular pathway for the heating vapor or steam along the 50 evaporator tube sections. The heating vapor flows through the system in counter-current to the liquid to be evaporated. The difficulty with this construction is that condensed steam is apt to clog the

long narrow pathway of the heating vapor 55 at one point or another. Evaporators of this type have a high evaporative capacity with a concomitant absorption of heat and the amount of condensate is considerable. It is necessary that the supply of steam or 60 heating vapor be ample and that it flow through the heating elements with as little friction or interruption as may be from bodies of condensate. It is the object of the present invention to provide means 65 whereby condensate in the heating elements may be by-passed downward from tier to tier out of the path of vapor in the narrow horizontal heating elements; the by-pass connections being so arranged as to give a 70 liquid seal to prevent flow of vapor therethrough.

In the accompanying drawing I have shown a simple and economical arrangement for this purpose.

75 In the drawing, Fig. 1 is a fragmental vertical section, certain parts being shown in elevation; Fig. 2 is a horizontal section along line 2—2 of Fig. 1, and Fig. 3 is a similar section along line 3—3 of Fig. 1.

80 As shown, the evaporator consists of four superimposed sections A, B, C and D; each section having a heating jacket and an evaporating tube therewithin. These tubes together constitute a continuous passageway 1 85 for liquor to be evaporated, liquid entering the system at 2 and concentrated liquor going to exit at 3. The several evaporator tube sections are end-connected at 4. The several jackets, 5, of the superimposed series are connected by 4-way crosses, 6. Steam, or heating vapor from a preceding effect, is admitted to the uppermost jacket through an upward-extending passageway of one of these crosses, and condensate and residual 90 vapor are discharged through the downwardly extending passage of the lowermost cross at the right, condensate being also discharged at the trapped downwardly extending passage of 10 at the left.

100 For the sake of simplicity of illustration, accessory connections enabling the device to work under vacuum or reduced pressure; liquor feed means; liquor discharge means; entrainment preventing means; connections 105 for working in multiple effect, etc., are omitted; but it is to be understood that the present evaporator can be used as a unit in any

of the usual assemblages of apparatus elements employed in evaporating liquids. Any other number of superimposed sections may be employed in lieu of the four shown.

5 In the apparatus shown, the liquid-sealed and trapped connections intermediate the jacket sections are provided by a 4-way cross of special construction. As shown, these crosses have up, down, right and left passages and are suitably flanged.

10 Referring more particularly to the cross in the lower right hand corner of Fig. 1, it will be noted that its upward passage is provided with a cup-like element 7 having a portion 8 extending past the plane of the flange, while the cross thereabove and flange-connected thereto has its downward passage similarly provided. The two elements 7 on coming together form a liquid-sealed trap 15 by means of extensions 8.

20 Steam or heating vapor entering the system at the top flows to the left through the uppermost heating jacket, then down through a 4-way cross to the jacket next below; and so on; flowing in countercurrent to the liquor passing through the evaporator tubes. In the course of this flow accumulating condensate is caught and drained 25 downward at various points through the liquid-sealed connections just described. This condensate is not at once taken out of the system, thereby complicating pressure relations, but flows through it to exit without interfering with steam flow. It will be 30 noted that at connections where condensate and steam flow together (see the connection 35 9 between B and C) the passageway is considerably larger in cross-section than that afforded by the annular clearance in the 40 jackets.

In lieu of the single evaporator tube section in each heating section, there may of course be a plurality of similar tubes in parallel.

45 What I claim is:—

1. In a countercurrent horizontal evaporator, a vertical series of horizontal liquor tubes each provided with a heating jacket, said heating jackets being arranged for flow 50 of heating vapor therethrough in series between an inlet for vapor on the uppermost jacket and an outlet for vapor and condensate on the lowermost jacket, said jackets including trapped by-pass connections inter-

cepting condensate at intervals and directing it towards said outlet. 55

2. In a countercurrent evaporator, a vertical series of horizontal evaporating end-connected tubes, a heating jacket for each such tube and a vertical connection between adjacent jackets at each end of said jackets, one such connection being open and the other trapped against flow of vapor, and the vertical connections being so arranged that heating vapor flows in series through the 60 several jackets while condensate is intercepted at intervals and by-passed downward to a common outlet for vapor and condensate. 65

3. In a countercurrent evaporator, a vertical series of horizontal, end-connected evaporator tubes, a heating jacket for each such tube and connections between such jackets, certain of such connections being open for free flow of vapor therethrough and 70 other connections being in the nature of 4-way crosses registering together, the registering arms of each such other pair of crosses carrying pockets which, together, 75 form traps for passage of condensed liquid. 80

4. In an evaporator comprising tubes for liquid to be evaporated and surrounding conduits for the heating medium, cross fittings for the said conduits, each cross having a plurality of passages and uniting flanges 85 and a cup-like element on one passage with one side of the cup-like element extending past the plane of a flange, whereby two such crosses may be united with the extended side of the cup-like element of one inside 90 the cup-like element of the other to form a liquid trap and seal. 95

5. In an evaporator comprising tubes for liquid to be evaporated and surrounding conduits for the heating medium, cross fittings for the said conduits, each cross having a plurality of passages and uniting flanges and a cup-like element in one passage with one side of the cup-like element 100 extending past the plane of a flange, whereby two such crosses may be united with the extended side of the cup-like element of one inside the cup-like element of the other to form a liquid trap and seal.

In testimony whereof, I have hereunto 105 affixed my signature.

RALPH MELLOR.
